CLAIM

The ornamental design for a small computer housing, as shown and described.

DESCRIPTION

FIG. 1 is a top right front perspective view of a small computer housing showing our new design;

FIG. 2 is a top left front perspective view thereof;

FIG. 3 is a top right front perspective view of a second embodiment thereof; and,

FIG. 4 is a top left front perspective view thereof. The rear elevational view is plain and unornamented.

FIG. 1

FIG. 2

FIG. 3

FIG. 4
